Specification for Design.

Patented June 1, 1920.

Application filed March 12, 1920. Serial No. 365,326. Term of patent 14 years.

To all whom it may concern:

Be it known that I, CHARLES RIEDER, a citizen of the United States, residing at the city and county of Philadelphia and State of Pennsylvania, have invented a new, original, and ornamental Design for a Chair, of which the following is a specification, reference being had to the accompanying drawings, forming part thereof.

Figure 1 is a perspective view of a chair showing my new design.

Fig. 2 is a side view thereof.

Fig. 3 is a rear view thereof.

Fig. 4 is a top view thereof.

I claim:

The ornamental design for a chair, as shown.

In testimony whereof I affix my signature hereto.

CHARLES RIEDER.
